UNITED STATES PATENT OFFICE.

GOTTFRIED WIRRER, OF PLAINFIELD, NEW JERSEY. ASSIGNOR TO INTERNATIONAL MOTOR COMPANY, OF NEW YORK, N. Y., A CORPORATION OF DELAWARE.

SEPARATOR AND VAPORIZER FOR INTERNAL-COMBUSTION ENGINES.

Application filed April 21, 1922. Serial No. 555,845.

The volatilizing of hydrocarbon fuels for internal combustion engines has presented the difficulty that while heat must be relied on mainly to effect the volatilization the mixture should be introduced into the firing chamber at a relatively low temperature commonly known as the dewpoint whereat its density is such as to provide in a theoretically fixed gas, the maximum thermal efficiency. Generally speaking, vaporization has been aided in known devices by taking up the fuel with heated air or by introducing a hot spot in the inlet manifold. Both of these methods have the disadvantage indicated above in that in both cases reliance is placed upon the adding of heat to the mixture with consequent expansion thereof and a loss of density.

The principal object of the present invention is to provide an apparatus for vaporizing hydrocarbons wherein the temperature of the mixture is kept within a predetermined range at all times and consideration given to the withdrawal therefrom of all unevaporated fuel and its volatilization and reintroduction into the mixture. In other words, the improvement herein seeks to provide primarily for the vaporization of all unevaporated fuel within the mixture by devices which act only on such unevaporated portion and insure its return to the inlet manifold after volatilization.

A further object of the invention is to provide an evaporating chamber which shall connect with the inlet manifold and constantly retain a sufficient quantity of fuel to facilitate starting when the motor is cold and supply a sufficient quantity of volatilized hydrocarbon for starting so long as the chamber is warm, and perhaps longer.

Still another object is to incorporate in an apparatus of the character described and for the practice of the improved method, a mechanical deflector to assist in atomization.

In the improved construction all of the desirable conditions and results mentioned briefly hereinbefore are attained without disturbing the normal metering of the fuel and the conventional metering devices may be employed advantageously. If desired, conditions surrounding the metering may be controlled to some extent by providing a degree of heat to the metering devices from the improved vaporizer.

Still another object is to provide suitable

means for taking advantage of the fact which is now established that hydrocarbon fuels when submitted to a relatively high temperature, that is, to any temperature through the approximate range of from 450° F. to 1425° F. will not crack but will vaporize at a substantially uniform rate at any temperature within that range and without alteration of the physical properties of the gas produced. To this end, the liquid fuel to be vaporized is subjected in the improved method and apparatus to the action of the exhaust gases from the motor.

It will be understood as the description proceeds that the invention is not to be limited to the incorporation of all of the subordinate features enumerated above nor to the precise design illustrated in the drawings and to be described hereinafter by way of example since the method as set out in the claims may be practiced in devices which may differ from those illustrated herein.

In the drawings:

Figure 1 is a somewhat conventional view partly in elevation and partly in vertical section showing the relation of the improved vaporizing chamber to the exhaust and inlet manifolds and to a source of fuel supply.

Figure 2 is a view in section through the vaporizing chamber illustrated in Figure 3.

Figure 3 is a view partly in section and partly in elevation through the inlet manifold and vaporizing chamber and taken on the plane indicated by the line 3-3 of Figure 1 and looking in the direction of the arrows.

Figure 4 is a detailed view in vertical section of a fragment of an exhaust manifold of modified construction for practicing the present invention.

The fuel to be vaporized may be supplied as usual through a carburetor indicated conventionally at *a*, a current of air meanwhile entering at *b* and passing over the jet *a'* for carburetion. The primary air entering at *b* is preferably heated in any known manner and its temperature preferably maintained substantially constant under different conditions as by means of a thermostat, in accordance with usual practice. While the invention is not to be limited to the temperatures employed it has been found in practice that about 160° F. is a most effective temperature when the air is introduced into the metering device, such as the venturi *b'*.

At this temperature sufficient heat is supplied by the air to vaporize a large percentage of the fuel without expansion and subsequent rarefaction of the mixture.

5 Practically all the heat supplied by the air will be absorbed in the vaporization of the fuel. After passing the metering device the mixture thus formed with the heavy ends in suspension passes on to the inlet manifold

10 c. In accordance with the invention it is proposed to withdraw the suspended heavy ends of the fuel including any that remains insufficiently atomized or is condensed, subjecting such withdrawn portion to a vaporizing heat provided by devices which do not directly act on the on-flowing mixture and then returning such vaporized fuel to the mixture. To this end, there is provided in the inlet pipe c', above the metering device

15 an annular groove c² which receives all such unevaporated liquid fuel. Centrally of the inlet pipe c' there is preferably mounted a generally conical deflector d against which the mixture strikes and its atomization

20 thereby facilitated. The form of this deflector d is preferably such with relation to the groove c² that as the mixture passes onward the liquid fuel therein will be thrown down into the groove c². Further, any con-

25 densed liquid fuel which may accumulate in the manifold riser or its branches will also be trapped in this groove, additional deflector ribs c⁷ being formed in the wall of the pipe c⁴. For convenience, the riser c⁴

30 may be curved upwardly from the pipe c' and afford a convenient support for the deflector d. The groove c² is inclined so that the liquid fuel condensed therein will flow by gravity into the improved vaporizing

35 chamber e which is supported in juxtaposition to the pipe c'. A discharge spout c⁵ may facilitate the flow of liquid fuel from the low point in the groove c² into the vaporizing chamber. Openings c⁶, e', in the pipe

40 c' and in the chamber e are disposed in alignment so as to facilitate the free flow of volatilized fuel from within the chamber e back into the mixture flowing through the riser c⁴. The vaporizing chamber e proper

45 is closed by an upper wall e² which may be of irregular form to increase its superficial area and by a lower wall e³. This chamber e is normally inclined to the horizontal and the lower wall e³ is preferably formed with

50 a series of pockets e⁴ which the liquid fuel therein may overflow successively to reach the lowest level. The spout c⁵ will discharge into the highest pocket e⁴. The effect of this construction is that if the chamber becomes

55 tilted in use the liquid fuel will not flow back into the groove c². Further, a large surface thereof is exposed to facilitate evaporation as will appear. Surrounding the chamber e may be directly formed pas-

60 sage e⁵, e⁶, for exhaust gases. In the

simplest construction the transverse walls e², e³, of the vaporizing chamber e will be disposed within the walls of the exhaust channels so that the liquid fuel within the vaporizing chamber e is fully exposed at top and bottom to the heat of these gases. When vaporized the fuel will, of course, pass through the aligned openings e', c⁶ back into the mixture the temperature of which is not directly affected by the exhaust gases which 70 vaporize that portion of the fuel which is withdrawn from the mixture.

The method described insures the maintenance of the most favorable operating conditions for the internal combustion engine 80 in that the mixture as finally introduced is at that temperature and condition which insures a density making for maximum thermal efficiency. The metering is done in accordance with conventional practice and 85 at a temperature which is most conducive to the formation of an effective mixture and the withdrawal of the liquid particles, and vaporization and their reintroduction into the on-flowing mixture are all accomplished 90 without in any way interfering with or changing the advantageous conditions under which the atomized mixture flows on into the motor.

It is proposed, under the most advantageous conditions, to subject the liquid fuel within the chamber e to a vaporizing heat from the exhaust gases which may vary in temperature through a wide range, as from approximately 450° F. to 1425° F. It has 95 now been established that hydrocarbon fuels when subjected to a temperature within this range will vaporize without undergoing any change in its physical properties and without cracking. In the preferred form of construction, therefore, the chamber e may be disposed directly within the main exhaust pipe although when applied to existing installations it may be convenient to divert a portion of the exhaust gases from the manifold f through a branch pipe f' which communicates with the portion of the exhaust pipe indicated at e⁶. In this construction the mouth of the pipe f' may be disposed directly within the exhaust manifold f as 100 105 110 115 shown more clearly in Figure 4.

One of the most important features of the invention will be understood by reference to Figure 2. As shown therein the lower wall e³ of the vaporizing chamber e is of comparatively thin metal at one end and of comparatively thick metal at the other end. Where this wall is inclined and formed with a series of overflow pockets the thin metal is preferably placed at the upper end and the thick metal at the lower end. The effect of this construction is that when the motor is first started, after being cold, the liquid fuel entrapped resting on the thin 120 125 portion of the wall will be quickly vapor- 130

ized, perhaps after a few blasts of the exhaust across the thin metal. On the other hand, after the motor has been running for some time, considerable heat is stored up in the thicker part of the wall where the mass of metal is greatest. This mass of metal will retain its heat for a comparatively long time and so serve to maintain a starting charge of vapor within the chamber. The invention is not to be limited to the particular form of the chamber nor to the relationship of its walls but in its broadest aspect contemplates a disposition of the metal which will meet the two conditions described.

Supplementary to the apparatus but not essential thereto is a heating coil indicated in Figure 2 at *k* which may be embedded in the wall *e*³ of the chamber *e* and have its leads *k*' connected with a source of electricity for heating the chamber and volatilizing enough of the fuel entrapped therein for starting when the motor is cold. To go a step further, it is practicable to provide an auxiliary source of supply indicated by the carburetor *l* and pipe *l*' for delivering liquid fuel into the chamber *e* in order that a starting charge independent of liquid entrapped by the chamber may be introduced into it at will.

As a manufacturing consideration it may be convenient to cast the exhaust pipe *e*⁶ and the chamber *e* as a short section having a flange *e*⁸ for engagement with a flange *b*² on the Venturi section. In this way, some heat may be lead from the exhaust gases in the pipe *e*⁶ through the metal of the section

*e*⁹ by conduction to the metal of the Venturi section for maintaining efficient temperature conditions in and about the metering device. The amount of heat thus transferred to the walls of the metering device and its consequent temperature may be regulated by insulating the Venturi section more or less from the flange *e*⁸, as will be understood.

What I claim is:—

1. An apparatus for producing a dry fuel mixture comprising a conduit adapted to be connected at one end to a metering device and at the other end to the cylinders of a combustion engine, a stationary conical deflector mounted centrally of said conduit and spaced from the wall thereof to permit the on-flow of the gaseous mixture, an annular groove in the wall of the conduit to receive deflected particles, an evaporating chamber separate and remote from the conduit, means for connecting the groove in the conduit to the evaporating chamber to conduct the liquid fuel collected in the groove to the evaporating chamber, a source of heat co-operating with the evaporating chamber to vaporize the collected liquid fuel, and means for returning the vaporized fuel to the conduit.

2. A structure according to claim 1 where-in the evaporating chamber is provided with a wall upon which the liquid fuel collects, the wall varying progressively in thickness from front to rear, with its greatest thickness at the rear thereof.

This specification signed this 18th day of April, A. D. 1922.

GOTTFRIED WIRRER.
